SLEEVE-VALVE INTERNAL-COMBUSTION
ENGINE

Frank Morgan Owner and Harry Thomas Underwood, Bristol, England, assignors to The Bristol Aeroplane Company Limited, Bristol, England, a British company

Application May 11, 1942, Serial No. 442,522
In Great Britain May 26, 1941

4 Claims. (Cl. 123—75)

This invention relates to internal-combustion engines of the kind in which the cylinder-ports are controlled by a sleeve, which is driven with a movement of combined reciprocation and oscillation so that each sleeve-port describes a closed curve with respect to the cylinder-wall. The cylinder-head end of the sleeve is in contact on the outside with the cylinder-barrel, and on the inside with the re-entrant cylinder-head, which parts enclose a chamber herein termed the "sleeve-pocket." It is desirable that the cylinder-ports, or at least the exhaust-port or ports, should be situated as near to the head as possible, and since the exhaust-port is controlled by a port in the sleeve-valve, the sleeve-valve itself extends beyond the port in it, so that the end of the sleeve never leaves the sleeve-pocket. There is a tendency for oil and other matter to accumulate in the sleeve-pocket, especially where the cylinder is disposed with the cylinder-head end downmost, and it is necessary to provide means to enable such accumulation to be discharged from the sleeve-pocket so that it does not obstruct movement of the sleeve. It is the object of the present invention to provide improved means for this purpose.

This invention comprises an internal-combustion engine of the type above-described, wherein the cylinder is formed with a passage opening to the inner end of the sleeve-port, and so positioned with respect to the travel of the sleeve-valve that a sleeve-port registers with it, whilst the sleeve-valve is moving inwards in the pocket, whereby material trapped in the pocket can escape into the sleeve-port. Preferably the construction is further characterised in that the said registration persists during substantially the whole of the movement of the sleeve-valve inwards in the pocket.

According to yet another feature of the invention, the positioning of the passage aforesaid is further characterised, in that registration of the sleeve-port and the said passage occurs, only whilst the sleeve-port is out of register with the cylinder-port which is controlled by the sleeve-port.

According to yet another feature of the invention, the cylinder is formed with a second passage opening at one end to the cylinder-port and extending into the sleeve-pocket, said passage being so positioned with respect to the first passage and to the travel of the sleeve, that whilst the sleeve-port is within the pocket, it registers simultaneously with the first passage and the second passage. Preferably such simul-

taneous registering occurs only whilst the sleeve-valve is moving inwards in the pocket. Preferably the positioning of the said second passage is yet further characterised in that the sleeve-port continues to register with the said second passage, until after the sleeve-port has opened the cylinder-port.

In the accompanying drawings:

Figure 1 is a diagrammatic view of the head end of a cylinder, showing the parts concerned with the present invention in sectional elevation,

Figures 2 to 6 are developed views looking from the inside of the cylinder, showing the cylinder exhaust-port, the passages aforesaid, and successive positions of the sleeve-valve and sleeve-port during a cycle of its movement.

Figure 7 is a diagrammatic view of a single cylinder engine embodying the invention.

Referring first to Figures 1 and 7, the head end of a cylinder is indicated at 10, with a re-entrant cylinder-head secured in it, and providing an annular space 12 constituting a sleeve-pocket, into which the sleeve-valve 13 enters. The combustion-chamber is bounded by the end 14 of the cylinder-head, and the crown of the piston 15. In the wall 10 of the cylinder there is indicated an exhaust-port 16, and this port is controlled by a port 17 in the sleeve-valve 13, the latter being reciprocated and oscillated within the cylinder by any known or convenient mechanism, indicated generally by the reference 28 in Figure 7.

The exhaust-port 16, of which there may be more than one, is positioned with its upper edge 18, aligned with the peripheral edge 14 of the cylinder-head 11 so that the whole area of the port is as near the cylinder-head as is convenient.

The exhaust-port 16 is controlled by the sleeve-port 17, which is spaced away from the end of the sleeve-valve, so that the latter never entirely leaves the sleeve-pocket.

A passage 19 constituted by a groove in the wall 10 of the cylinder, extends from the end of the sleeve-pocket beyond the innermost position of the sleeve-valve, towards the combustion chamber into which it opens at the end 20. Preferably this end is enlarged at 21 (see Figure 2) into a peripheral groove of short annular extent. A second passage 23 also constituted by a groove formed in the cylinder wall, opens at one end into the exhaust-port 16, and its other end lies within the sleeve-pocket. These grooves or passages 19, 23 are formed on the inner surface

of the wall of the cylinder 10, and since the outer circumferential surface of the sleeve 13 bears on the cylinder-wall, it will be appreciated that these passages, although each opens at one end, namely the passage 19 to the sleeve-pocket 12 and the passage 23 to the exhaust-port 16, do not provide any throughway conduit except when the sleeve-port 17 registers with them, as herein-after described.

Referring now to Figures 2 to 6, the developed views of the various parts are indicated by the same references as in Figure 1, namely the cylinder-wall 10 with the exhaust port 16 formed in it, the sleeve-valve 13 with the port 17 formed in it, the passages 19 and 23 formed in the cylinder-wall 10, and there is also shown a datum-line 24, corresponding to the peripheral edge 14 of the cylinder-head 11, with which the upper edge 18 of the exhaust-port 16 is aligned. The path of movement of the sleeve-valve is indicated by the broken line 25, this being the path of the point 26 near the top of the port 17 (see Figure 2), which traverses the path 25 in an anti-clockwise direction.

The disposition of the passages 19 and 23 is determined with respect to the path of movement and shape of the sleeve-port 17, as will now be described. In Figure 2 the sleeve-valve 13 is shown in the position it occupies just after the exhaust-port 16 of the cylinder has been closed, and the sleeve-valve 13, is commencing its movement inwards into the sleeve-pocket. At this point, the port 17 opens to the extension 21 of the passage 19, so as to provide communication from the interior of the sleeve-pocket to the combustion-chamber, and permit the discharge of any matter accumulated in the sleeve-pocket into the port 17; it may pass therefrom into the combustion-chamber, or if the quantity is but small, will accumulate in the port 17 on the lower edge 40 thereof.

This transfer of matter from the sleeve-pocket 12, continues during the upward movement of the valve to the position shown in Figure 3, it being appreciated that the said matter is displaced from the sleeve-pocket by the inward movement of the valve thereto. In the position shown in Figure 3, the lower edge 21 of the port 17, has just passed upwards above the datum-line 24, so that the port 17 is now entirely closed, by the cylinder-wall on its outer side, and by the cylinder-head on its inner side, but the second passage 23 is so disposed, that at this point the port 17 commences to open to it.

Figure 4 shows a further stage in the movement of the sleeve 13, at which the passage 23 is open to the port 17, so that any material contained in the sleeve-port 17, can escape through the passage 23 to the exhaust-port 16, which is of course shut off from the combustion-chamber by the solid wall of the sleeve-valve 13, but is open to atmosphere at its outer side. Any further matter forced out of the sleeve-pocket 12 into the passage 19 by the continued inward movement of the valve 13, is thus delivered into the exhaust-pipe instead of being delivered into the combustion-chamber.

The discharge of matter from the pocket 12 continues in this way, until the valve reaches its inmost position in the sleeve-pocket, as shown in Figure 5, at which point its port 17 moves out of register with the passage 19, whilst, however, still remaining in register with the passage 23.

When the valve is moving from the position shown in Figure 5 to the position shown in Fig-

ure 6, and thence to near the position shown in Figure 2, it is moving outwards from the sleeve-pocket, so that there is no need to provide for the discharge of any material therefrom, and during this period the lower end of the passage 19 is closed by the solid wall of the sleeve-valve. During the movement from the position shown in Figure 5 to the position shown in Figure 6, any material which has been forced into the sleeve-port 17, can drain out through the passage 23 to the exhaust-port and out of the engine, until the port 17 commences to open the exhaust-port 16, as shown in Figure 6. At this point the exhaust-gases, after a power-stroke of the engine, begin to be discharged through the two ports, and sweep out with them any matter in the port 17, and this action can continue during the whole period during which the exhaust-port 16 is opened by the sleeve-port 17.

The movement of the sleeve 13 continues until the exhaust-port 16 is closed, and the various parts returned to the position shown in Figure 2 on completion of the cycle of operations of the valve, and the same cycle is then repeated.

The whole operation of the discharge of unwanted matter from the sleeve-pocket may be briefly described as follows: The sleeve-port 17 acts as a travelling conduit and the matter is discharged into it, and possibly into the combustion-chamber as soon as the sleeve commences its movement inwards into the pocket. As soon as communication between the sleeve-port and the combustion-chamber is cut off, a fresh path of discharge to the second passage 23 and thence to the exhaust-port is opened, and this remains open until the exhaust-port itself is opened by the sleeve-port, so that any matter present is blown out by the exhaust-gases into the exhaust-passage.

The timing of the movement of the sleeve relatively to the movement of the piston, is approximately that Figure 2 shows the commencing of the inlet stroke, Figure 3 is approximately the beginning of the power-stroke when combustion is taking place in the cylinder, Figures 4 and 5 show the power-stroke, and Figure 6 the commencement of the exhaust-stroke. It will be seen, therefore, that at no time is there direct communication between the sleeve-pocket and the exhaust gases in the cylinder, or in the exhaust-passage, and that throughout the inward stroke of the sleeve into the sleeve-pocket, there is provided an outlet for matter discharged from the pocket either into the sleeve-port, or through it into the combustion-chamber, or to the exhaust-port.

Finally, it will be understood that since the sleeve-port is open to the passage 19 during substantially the whole of the inward movement of the sleeve-valve, if the quantity of matter to be dealt with is not too great but can be accommodated within the sleeve-port, it will be unnecessary to use the second passage 23, since the unwanted matter can be accumulated in the sleeve-port, and driven out therefrom by the opening of the exhaust-port.

We claim:

1. In a four-stroke internal-combustion engine, a cylinder having a re-entrant head to provide a sleeve-valve pocket, a sleeve-valve having a combined reciprocating and oscillating movement within the cylinder with its end accommodated within the pocket, and a piston reciprocable within the sleeve-valve, which cylinder and sleeve-valve are formed with co-operating ex-

haust ports, and which cylinder is formed with a passage opening to the inner end of the pocket, and so positioned with respect to the travel of the valve that it registers with the exhaust port in the sleeve-valve whilst the valve is moving inwards in the pocket, and that it is covered by the sleeve valve during the power and exhaust strokes of the piston in the cylinder.

2. In an internal-combustion engine, a cylinder having a re-entrant head to provide a sleeve-valve pocket, and a sleeve-valve having one end fitting with the pocket, and having a combined reciprocating and oscillating movement within the cylinder and pocket, which cylinder and sleeve-valve have co-operating exhaust ports, and which cylinder is formed with a passage opening into the inner end of the pocket, and so positioned with respect to the travel of the sleeve-valve as to register with the exhaust port in the sleeve-valve during substantially the whole of the movement of the sleeve-valve inwards in the pocket and to be covered by the sleeve-valve during the remainder of the movement of the latter.

3. In an internal-combustion engine, a cylinder having a re-entrant head to provide a sleeve-valve pocket, and a sleeve valve having a com-

bined reciprocating and oscillating movement in the cylinder, and having one end fitting within the pocket, which cylinder and sleeve valve are formed with co-operating exhaust ports, and

5 which cylinder is formed with a first passage opening to the inner end of the pocket and so positioned with respect to the travel of the sleeve-valve as to register with the exhaust port therein, while the valve is moving inwards in the 10 pocket, and to be covered by the valve while it is moving outwards in the pocket, and with a second passage opening to the exhaust port in the cylinder, and so positioned with respect to the travel of the valve as to register with the exhaust 15 port therein during the portion of the movement of the sleeve-valve into the pocket after the exhaust port therein has fully entered the pocket, and no longer communicates with the interior of the cylinder.

20 4. The subject matter of claim 3, wherein the second passage is so positioned that it continues to register with the exhaust port in the sleeve-valve until the said port again registers with the port in the cylinder.
